UNITED STATES PATENT OFFICE.

HARRY C. ADAM, OF ST. LOUIS, MISSOURI.

LIGHTING-FIXTURE.

1,307,572.

Specification of Letters Patent. Patented June 24, 1919.

Application filed October 8, 1918. Serial No. 257,357.

To all whom it may concern:

Be it known that I, HARRY C. ADAM, a citizen of the United States, residing at St. Louis, Missouri, have invented a certain new and useful Improvement in Lighting-Fixtures, of which the following is a full, clear, and exact description, such as will enable others skilled in the art to which it appertains to make and use the same.

10 This invention relates to lighting fixtures of the type in which an electric lighting unit is inclosed in a diffusing bowl and an opaque canopy or shell that supports the bowl and serves as a closure for the open 15 upper end of the bowl.

The main object of my present invention is to provide a lighting fixture of the general type referred to that is designed for use with a concentrated filament incandescent lamp and which is constructed in a novel manner that insures the major portion of the horizontal, approximately horizontal and upwardly inclined rays emitted from the lamp being reflected downwardly into 25 the useful plane.

Another object is to provide a lighting fixture having the characteristics above referred to that softly illuminates the ceiling above the fixture; that presents a neat and ornamental appearance; that can be manufactured and sold at a low cost; that can be taken apart and assembled easily and which is so constructed that the metal parts of same can be used successfully with different 35 sized lighting units and different sized diffusing bowls by simply raising or lowering the part that carries the diffusing bowl so as to maintain the proper relation between the lighting unit, the diffusing bowl and the 40 reflector which is arranged above the filament of the lighting unit. Other objects and desirable features of my invention will be hereinafter pointed out.

Figure 1 of the drawings is a view partly 45 in vertical section and partly in elevation of a lighting fixture constructed in accordance with my invention; and

Fig. 2 is a detail sectional view, illustrating a slight modification of my invention.

50 Referring to Fig. 1 of the drawings, which illustrates the preferred form of my invention, A designates the diffusing bowl of my improved lighting fixture which is preferably formed of translucent glass, B designates the lighting unit consisting of a concentrated filament incandescent lamp, com-

monly termed a nitrogen gas filled lamp, C designates a shell or canopy formed of sheet metal or other suitable opaque material that supports the bowl A and serves as 60 a closure for the open upper end of said bowl, D designates a reflecting surface that is arranged above the filament x of the lighting unit and E designates an electrical receptacle that carries the lighting unit B. 65

The fixture can either be mounted upon or arranged in close proximity to the ceiling of a room, or it can be suspended from the ceiling by a chain or other suitable means. Furthermore, the parts previously referred 70 to, which constitute the essential elements of my improved fixture, can be combined or connected together in various ways without departing from the spirit of my invention. The diffusing bowl A is preferably of substantially the form shown in Fig. 1 and is provided with a concavo-convex lower portion 1 and an upper portion 2 of substantially frusto-conical shape in general outline whose base is of greater diameter than 75 the lower portion 1 of the bowl and connected to said lower portion by a part 3 that is disposed in a substantially horizontal plane. In other words, the bowl A consists of a hemispherical-shaped lower portion 1 80 whose upper edge merges into an outwardly flared part 3, which, in turn, merges into a frusto-conical-shaped part 2 that projects inwardly over the lower portion 1 of the bowl. The upper and lower portions of the 85 bowl can either be formed separately or integrally connected together, and the outer surface of the bowl can either be plain or ornamented. The opaque shell C, which serves as a closure for the open upper end 90 of the bowl and also as a housing for the lighting unit B, can be of any preferred shape, but I prefer to use a shell of substantially bell shape or frusto-conical form and provide the lower end of said shell with 95 a rim or depending flange 4 that fits over a flange 5 at the upper edge of the bowl A, the bowl being connected to the shell C in any suitable manner, such, for example, as by means of thumb screws 6 in the flange 4 100 of the shell that engage the flange 5 at the upper edge of the bowl A. The reflecting surface D can either consist of a separate reflecting member, as herein shown, or a coating of suitable material on the inner side 105 of the shell C. The bowl A and the lighting unit B are so positioned with relation

100

105

110

to each other that the main portion of the downwardly inclined, oblique rays from the lighting unit, indicated by the lines *w* in Fig. 1, will pass through the lower portion 1 of the bowl. Most of the rays which are emitted from the lighting unit at such angles that they will not pass directly through the lower portion 1 of the bowl are also utilized to illuminate the space beneath the fixture, thereby producing a fixture in which the major portion of the rays from the lighting unit are directed downwardly into the useful plane. I accomplish this by providing the fixture with a substantially cone-shaped or bell-shaped reflecting surface, preferably formed by a reflecting member D that surrounds the lighting unit at a point above the filament *o* of the lighting unit and by providing the diffusing bowl with a substantially frusto-conical-shaped upper portion 2 of greater diameter than the lower portion of the bowl which is positioned between the reflector D and the lower portion 1 of the bowl. The major portion of the rays that are emitted from the lighting unit above the angle of 90° strike the reflector D and are reflected downwardly from same either directly through the lower portion of the bowl or through the base portion of the frusto-conical-shaped upper part 2 of the bowl, as indicated by the lines *y* in Fig. 1. The rays that are emitted from the lighting unit at the approximate angles indicated by the line *z* in Fig. 1 strike the inwardly inclined upper part 2 of the bowl and are reflected downwardly from same through the part 3 of the bowl and the base portion of the frusto-conical-shaped top part 2 immediately adjacent the same. It will, of course, be understood that many of the light rays are absorbed by the reflector D and by the top portion 2 of the bowl, and further, that not all of the rays will travel in the particular directions indicated by the three groups of lines *w*, *y* and *z*, but in practice the major portion of the rays travel in the manner indicated by the lines *w*, *y* and *z*, thereby causing most of the rays from the lighting unit to be utilized to illuminate the space beneath the fixture where the light is most needed. When the fixture is intended to be mounted upon or arranged in close proximity to the ceiling of a room I prefer to equip the fixture with a ceiling canopy that is adapted to be connected to a ceiling outlet box G, or other suitable supporting structure in the ceiling, by means of screws 7. The shell C can be connected to said ceiling canopy in various ways without departing from the spirit of my invention, but for the sake of economy in manufacture and ease in assembling and disassembling the fixture, I prefer to clamp the shell C and the ceiling canopy F together and also secure the electrical receptacle E in operative position by

means of a clamping ring 8 that is mounted on an externally screw-threaded portion 9 on the electrical receptacle E. As shown in Fig. 1 of the drawings, the shell C is provided with a top wall 10 that bears against the underside of the ceiling canopy F, said abutting portions having aligned openings in same up through which the externally screw-threaded portion 9 of the electrical receptacle can be inserted. After the shell C, ceiling canopy F and electrical receptacle E have been combined in the manner described, the retaining ring 8 is screwed downwardly onto the externally screw-threaded portion 9 of the electrical receptacle so as to securely clamp the abutting portions of the canopy and shell together and clamp them between the retaining ring 8 and a flange 9a on the electrical receptacle. If the fixture is designed to be suspended from the ceiling by means of a chain or other device the ceiling canopy F can be omitted and the receptacle E can be clamped to the shell C by means of an internally screw-threaded cap that is screwed onto the upwardly-projecting portion 9 of the electrical receptacle.

In order that the metal parts of the fixture may be used with different sized lighting units and different sized diffusing bowls, I have constructed the shell C in such a manner that the lower part of said shell and the diffusing bowl A can be raised and lowered relatively to the top part of the shell C to which the electrical receptacle E is connected, thereby enabling the proper relation between the lighting unit B, the reflector D and the bowl A to be maintained with different sized lighting units and diffusing bowls. One convenient way of accomplishing this desirable result is to provide the shell C with a top portion C' that is arranged in telescopic engagement with the lower portion of said shell and which is connected to same by suitable fastening devices 11, preferably screws that are mounted in the lower portion of the shell and which are adapted to be screwed into one of a plurality of sets of internally screw threaded holes 12 that are arranged in the top portion C' in different horizontal planes. If a medium sized lighting unit is used, the lower portion of the shell C is arranged in the manner shown in Fig. 1, namely, with the screws 11 in the intermediate set of holes 12. When a large sized lighting unit is used, the lower portion of said shell is moved downwardly far enough to permit said screws to be inserted in the bottom set of holes 12, said bottom set of holes being spaced far enough below the intermediate set of holes 12 to compensate for the additional length of the lighting unit, and thus maintain the proper relation between the lighting unit and the upper portion 2 of the diffusing bowl. When a small sized lighting unit is used the

- lower portion of the shell C is moved upwardly far enough to enable the fastening devices 11 to be inserted in the top set of holes 12 in the upper portion C' of the shell, 5 thereby maintaining substantially the same relation between the lighting unit and the upper portion of the bowl as is maintained when a medium sized or a large sized lighting unit is used.
- 10 It is immaterial how the reflector D is retained in operative position, and while the particular curvature of said top reflector is immaterial, I prefer to make it substantially cone-shaped or bell shaped in outline. The 15 reflector D can either be provided at its upper end with an inwardly projecting flange 13 that surrounds and bears upon the lamp B in proximity to the point where the neck portion of the lamp starts, or the reflector D can be secured to the shell C, as 20 shown in Fig. 2, by means of fastening devices 13^a in the shell that engage a flange or ring 13^b at the upper end of the reflector.

A lighting fixture of the construction 25 above described has a high degree of efficiency, in that the rays emitted from the lighting unit at upwardly inclined angles and in horizontal and substantially horizontal planes are utilized principally to illuminate 30 the space beneath the fixture. Such a fixture presents a neat and ornamental appearance; it softly illuminates the ceiling above the fixture; it can be manufactured and sold at a low cost and it can be easily assembled 35 or disassembled, thereby greatly facilitating cleaning of the fixture and also installation or removal of the fixture.

Having thus described my invention, what I claim and desire to secure by Letters Patent is:

- 40 1. A lighting fixture, comprising a bowl provided at its upper end with an upwardly inclined light diffusing and reflecting portion that projects inwardly over the lower portion of the bowl, an opaque shell that serves as a closure for the opening in the upper end of the bowl, an electric lighting unit arranged in the space inclosed by said shell and bowl and positioned with relation 45 to the bowl so that its filament lies in a higher horizontal plane than the major part of the upwardly inclined portion of the bowl, and a substantially cone-shaped reflecting surface arranged inside of said shell 50 in close proximity to the filament of said lighting unit and at a point above the inwardly inclined upper portion of the bowl, for the purpose described.

2. A lighting fixture, comprising a diffusing bowl provided at its upper end with a substantially frusto-conical-shaped light diffusing and reflecting portion of greater diameter than the lower portion of the bowl, 60 a shell that serves as a closure for the open upper end of the bowl, an electric lighting unit arranged inside of said shell in such a position that most of the horizontal and downwardly inclined rays which are emitted from said lighting unit will either pass through the lower portion of the bowl or 65 will strike the frusto-conical-shaped upper portion of the bowl and be reflected downwardly by same, and a reflecting surface arranged inside of said shell in sufficiently close proximity to the filament of the lighting unit to cause the upwardly inclined rays emitted from the lighting unit to be reflected downwardly.

3. A lighting fixture, comprising a diffusing bowl having a substantially hemispherical shaped lower portion and a substantially frusto-conical-shaped upper portion whose base is of greater diameter than the lower portion of the bowl, the upper and lower portions of the bowl being translucent, an opaque shell that serves as a closure for the open upper end of the bowl, a lighting unit consisting of a concentrated filament incandescent lamp arranged between the shell and the bowl, with its filament positioned at or above the top edge portion of the bowl, and a substantially bell shaped reflector arranged inside of the shell in such a position with relation to the lighting unit that it will reflect downwardly through the bowl most of 90 the rays that are emitted from the lighting unit above the angle of 90°.

4. A lighting fixture, comprising a diffusing bowl provided at its upper end with an upwardly inclined light diffusing and reflecting portion of greater diameter than the lower portion of the bowl which projects inwardly over said lower portion, an opaque shell that carries said bowl and serves as a closure for the open upper end of the bowl, 100 an electrical receptacle arranged in the upper portion of said shell and adapted to receive an incandescent electric lamp, and a substantially bell shaped reflector arranged inside of said shell with its lower edge portion 105 flaring outwardly away from the filament of the lighting unit and terminating in approximately the same horizontal plane in which said filament lies.

HARRY C. ADAM.
